UNITED STATES PATENT OFFICE

2,395,637

COMBINATION LADDER

Thomas C. McCoy, San Antonio, Tex.

Application February 5, 1945, Serial No. 576,191

1 Claim. (Cl. 228—23)

This invention relates to ladders and has for its object to provide a combination step-ladder and straight away ladder.

Another object of the invention is to provide a ladder for reaching high position and which may be quickly converted into a step-ladder.

A further object of the invention is to provide a ladder comprising a plurality of members so arranged that all may be locked together by very simple means.

Other features and advantages will become more readily apparent from the following description and the accompanying illustrative drawings in which:

Figure 1 is a side elevation of my improved ladder shown as a straight ladder.

Figure 2 is a similar view of the same shown as a step ladder.

Figure 3 is a front elevational view of Figure 1.

Figure 4 is an elevational view of the ladder shown in collapsed position.

Figure 5 is a detail view of a combined shelf and brace, and

Figure 6 is a detail perspective view of the shelf.

In the accompanying drawings as above enumerated and in the following specification, like characters of reference indicate like parts throughout and in which 10, indicates my improved household ladder which consists of ladder sections 11 and 12, the side bars 13 and 14, of section 11, being flared apart at their foot ends 15 and 16, and the free ends 17 and 18, of the side bars 19 and 20, being similarly flared apart. The upper ends 21 and 22, of members 13 and 14, are parallel and have pivotally connected thereto by bolts 23 and 24, at points about twelve to eighteen inches below the extreme terminals 25 and 26, thereof the extreme upper terminals 27 and 28, of the members 19 and 20, which are also parallel at this point and which fit snugly between said parts 21 and 22, when the member 12 is raised to aligned position with member 11, to

form a straight ladder, designated as a whole by character 29. The upper portions 30 and 31, of said members 19 and 20, are held braced to member 11, by means of the uppermost step 32, thereof, whereby the members 11 and 12, when aligned and the ends 17 and 18, leaned against a wall or other support are held rigidly connected.

Pivots connected to members 19 and 20, are arms 32 and 33, to which is secured a shelf 34, the outer edge 35, of which is provided with spaced apart cut-outs 36 and 37, into which are screwed hooks 38 and 39, adapted for engagement with projecting screw-eyes 40, in the extending ends 41 and 42, of step 43, when the device is used as a step-ladder as indicated in Figure 2 of the drawings. A button 44, is pivotally connected at 45, to the upper part 22, of the member 14, to further secure the members 14 and 20, in place when the latter member is in up position.

It is thought that persons skilled in the art to which the invention relates will be able to obtain a clear understanding of the invention after considering the description in connection with the drawings. Therefore, a more lengthy description is regarded as unnecessary.

Minor changes in shape, size and rearrangement of details and parts such as come within the purview of the invention claimed may be resorted to, in actual practice, if desired.

Having now described my invention that which I claim as new and desire to procure by Letters Patent is:

A ladder formed of two pivotally connected sections, one being an extension section, a shelf pivotally connected to the latter section and having recesses in its free transverse edge, hooks located in the recesses, eyes on a step of the other section adapted to be engaged by the hooks, a button on the latter section adapted to engage the extension section when in raised position.

THOMAS C. MCCOY.
